UNITED STATES PATENT OFFICE.

ELIHU BOWLIN, OF CHATTANOOGA, TENNESSEE, ASSIGNOR OF ONE-HALF TO EDWIN J. BALDWIN, OF EAST CHATTANOOGA, TENNESSEE.

REVERSIBLE DISK PLOW.

1,152,279.

Specification of Letters Patent. Patented Aug. 31, 1915.

Application filed November 10, 1914. Serial No. 871,376.

To all whom it may concern:

Be it known that I, ELIHU BOWLIN, a citizen of the United States, residing at Chattanooga, in the county of Hamilton and State of Tennessee, have invented new and useful Improvements in Reversible Disk Plows, of which the following is a specification.

This invention relates to reversible disk plows and it consists in the novel features hereinafter described and claimed.

An object of the invention is to provide a plow comprising a wheel mounted frame with a head turnably mounted thereon and of special design, there being a standard and soil engaging element carried by the head.

In the accompanying drawings:—Figure 1 is a top plan view showing the parts of the plow in one position. Fig. 2 is a similar view showing the parts of the plow in another position. Fig. 3 is a transverse sectional view of parts of the plow. Fig. 4 is a perspective view of the parts shown in Fig. 3. Fig. 5 is a perspective view of means provided upon the plow for carrying the land wheel. Fig. 6 is a detail side elevation of a part of the plow with parts in section. Fig. 7 is a detail sectional view of one of the furrow wheel supports of the plow.

The frame of the plow includes a beam 1 having angularly disposed end portions 2. An approximately semicircular beam 3 is provided at one side of the beam 1 and is disposed at the opposite side of the intermediate portion of the beam 1 from the end portions 2 of the said beam 1.

A bracket 4 is provided at the side of the beam 1 at a point midway between the ends of the beam 3 and at the opposite side from the said beam 3. The said bracket 4 is provided at its top side with an arcuate groove 5 and at its outer and upper edge with a socket 6 having an arcuate inner vertical wall. The arc of the groove 5 and the arc of curvature of the wall of the socket 6 are approximately struck from the same center as the arc of curvature of the beam 3.

A block 7 is provided at the side of the beam 1 and a tongue 8 is pivotally mounted upon the said block at a point approximately at the center of the arc of curvature of the beam 3 and the said tongue extends transversely across the beam 3. A tooth 9 is provided at the inner or rear end of the tongue 8 and the said tooth is radially dis-

posed with relation to the pivot upon which the tongue swings and is also in alinement with the median longitudinal dimension of the tongue. An axle 10 is pivoted to the beam 3 at a point midway between the ends thereof and the said axle is provided at its inner portion with a longitudinally disposed slot 11. A pin 12 is provided upon the tongue 8 and enters the said slot 11 and is adapted to move along the same when the tongue 8 is swung over the beam 3. A land wheel 13 is journaled at the outer end of the axle 10 at a point beyond the outer side of the beam 3. The land wheel 13 may be journaled upon a crank spindle 14 which in turn may be secured to the axle 10 and thus means is provided for adjusting the center of the land wheel 13 with relation to the axle 10 and beam 3. When it is desired that the beam 3 should be positioned relatively close to the ground the crank of the spindle 14 is positioned to one side or the other of the axle 10 and consequently the center of the land wheel 13 is in close proximity to the beam 3. When it is desired that the beam 3 should be positioned at an elevated point with relation to the ground the crank of the spindle 14 is positioned immediately below the axle 10. Any suitable securing device may be provided for holding the spindle 14 at an adjusted position with relation to the axle 10 as for instance that shown in Fig. 5 of the drawing.

A head 15 is mounted upon the bracket 4 and is provided at its under side with flanges 16 which enter the groove 5 and socket 6. The outermost flange 16 is provided at its inner side and upper portion with a recess 17 in which a shoulder 18 provided upon the curved wall of the socket 6 snugly fits. The head 15 is provided at its outer end with a vertically disposed groove 19 having converging side walls. A standard 20 is slidably mounted in the groove 19 and is provided with chamfered edges adapted to fit snugly against the converging side walls of the said groove. A disk 21 is journaled for rotation at the lower portion of the standard 20. A lever 22 is fulcrumed upon the head 15 and its working end is pivotally connected with the standard 20. By swinging the lever 22 the disk 21 may be raised above the surface of the soil and hence the tongue may be readily turned around at the end of a furrow.

One end of a link 23 is pivotally connected with the tongue 8 at one side of the point at which the said tongue is pivotally connected with the block 7 and the other end of the said link 23 is pivotally connected with the head 15 at a point within the inner most flange 16. The head 15 is provided at its inner end with a pair of teeth 24 which are adapted to receive between them the tooth 9 as the tongue is swung over the beam 3.

Brackets 25 are mounted upon the angularly disposed end portions 2 of the beam 1 and a shaft 26 is journaled in each bracket 25. The shafts 26 carry at their lower ends spindles 27 upon which furrow wheels 28 are journaled. Arms 29 are secured to the upper portions of the shafts 26 at points above the brackets 25 and a bar 30 pivotally connects the inner ends of the arms 29 together. The intermediate portion of the bar 30 is pivotally connected with the link 23 and the head 15 at the point of pivotal connection between the said link and head.

An operator's seat 31 is mounted upon the inner end of the tongue 8 and the said tongue is provided with a pivoted clip 32 which is adapted to enter notches 33 provided at the end portions of the beam 1.

The operation of the plow is as follows: When the operator who occupies the seat 31 depresses one end of the clip 32 the said clip is disengaged from one of the notches 33 and then the draft animals which are connected with the tongue 8 are driven around the outer side of the beam 3. Thus the free end of the tongue 8 is swung around the beam 3 and the link 23 is moved longitudinally. This movement on the part of the link 23 will turn the head 15 upon the block 7 and the turning movement on the part of the head will reverse the position of the standard 20 and disk 21 with relation to the beam 1. As the tongue 8 and head 15 turn as above indicated the tooth 9 carried at the end of the tongue will enter the space between the teeth 24 provided upon the head and consequently when the tongue 8 is moving along the intermediate portion of the beam 3 the said tongue is positively connected with the head by reason of the said intermeshing teeth and the link 23 is assisted in imparting a turning movement to the head. During the time that the tongue 8 is moving from one end of the beam 3 to the other the pin 12 carried by the said tongue and which is received within the slot 11 of the axle 10 will swing the said axle

upon its pivotal connection with the beam 3 so that the wheel 13 carried at the outer end of the said axle is swung with relation to the frame of the plow of which the beams 1 and 3 are component parts. As the link 23 is moved longitudinally as hereinbefore described the bar 30 will be given a similar movement which in turn will swing the arms 29 and inasmuch as the said arms are fixed to the shafts 26 the said shafts are turned in the brackets 25 whereby the furrow wheels carried at the lower ends of the shafts 26 are turned with relation to the frame of which the beams 1 and 3 are components. Therefore it will be seen that during the time that the disk is reversed from one position to another with relation to the frame of the plow the furrow wheels and the land wheel are simultaneously swung or turned in order that they may be properly positioned with relation to the frame and the line of draft as the direction of the tongue is changed with relation to the frame.

Having described the invention what is claimed is:—

1. A plow comprising a frame having a bracket provided with an arcuate groove which opens at its ends at the ends of the bracket, a head having a flange slidably received in the groove, a standard carried by the head and a disk carried by the standard.

2. A plow comprising a frame provided with a bracket having an arcuate groove and socket open at their ends, a head provided with flanges which enter the groove and the socket, one of the said flanges being provided with a recess, the wall of the socket having a shoulder which enters the recess, a standard carried by the head and a disk journaled upon the standard.

3. A plow comprising a frame, a head turnably mounted thereon, a soil engaging element operatively connected with the head, said head being provided at its inner end with a pair of spaced teeth, a tongue pivoted upon the frame and provided at its inner end with a tooth adapted to enter the space between the teeth of the head and a link pivotally connected at one end with the tongue and at its other end with the head.

In testimony whereof I affix my signature in presence of two witnesses.

ELIHU BOWLIN.
